UNITED STATES PATENT OFFICE

2,460,940

METHOD OF AND APPARATUS FOR TREATING SHOES WITH STEAM AND HOT AIR

Mieth Maeser, Beverly, Mass., assignor to United Shoe Machinery Corporation, Flemington, N. J., a corporation of New Jersey

Application January 14, 1948, Serial No. 2,268

8 Claims. (Cl. 12—1)

1

This invention is concerned with the problem of conditioning thermo-plastic toe-stiffeners of partially fabricated shoes for toe-lasting. One of the factors involved in this problem is the time element predicated upon the potential output of six shoes per minute by a toe-lasting machine of the type set forth in United States Patent 2,324,509, granted July 20, 1943, on application of B. Jorgensen.

A conditioning apparatus of two-shoe capacity must be capable of softening a toe-stiffener in $\frac{1}{3}$ minute to keep pace with a lasting machine of the type above specified. Since a large proportion of the inner surface of a toe-stiffener is obstructed by a last, nearly all the heat required by the area so obstructed must be conducted to it by the vamp, which, itself, constitutes a heat barrier that must be heated at a very rapid rate. Dry heat of sufficient intensity to penetrate a vamp of chrome-tanned skin and soften a toe-stiffener thereunder in $\frac{1}{3}$ minute would burn the vamp, but steam at 260° F. will not only penetrate such a vamp without burning it but will soften a toe-stiffener in $\frac{1}{3}$ minute. Still, that alone would not solve the problem if the insole were also subjected to steam at a temperature required by the toe-stiffener.

The reason is that vegetable-tanned leather (of which insoles are made) would be burned by steam or by visible water-vapor (commonly termed "steam") at any temperature above 167° F. Reduced to simple terms, then, the problem is to soften a thermo-plastic toe-stiffener in $\frac{1}{3}$ minute without damaging a vamp of chrome-tanned skin or an insole of vegetable-tanned leather.

Therefore, the invention provides an improved treatment for softening a thermo-plastic toe-stiffener in a partially fabricated shoe, the treatment consisting in flowing steam in atmosphere on the outer surface of the vamp, and simultaneously flowing hot dry air on the bottom of the insole in sufficient volume and with sufficient velocity to prevent the steam from wetting the insole. The moisture content of the steam may thus be used to accelerate the conduction of heat through the vamp and the toe-stiffener while the hot air flowing on the insole not only protects the latter against being wetted by the steam but supplies its own heat to the interior surface of the lasting margin of the toe-stiffener. Tests of treatment in accordance with the invention have demonstrated that a temperature of 356° F. will not burn a vegetable-tanned insole in $\frac{1}{3}$ minute if the insole is quite dry, also that such insoles

2

may tolerate very small quantities of moisture at temperatures not far below 356° F.

Referring to the drawings,

Fig. 1 is a diagrammatic representation of an apparatus for treating shoes according to the present invention, the treatment unit being represented partly in front elevation and partly in section;

Fig. 2 is a vertical section of the treatment unit (see line II—II in Fig. 1);

Fig. 3 is an inverted horizontal section of the treatment unit, turned 90° clockwise (see line III—III in Fig. 2);

Fig. 4 is a sectional elevation, on a larger scale of the elements constituting a treatment station; and

Fig. 5 is a sectional plan view of an assemblage of needle valves and other elements by which air and steam are heated, directed and regulated.

20 A typical example of the type of shoe for which the present invention is intended is illustrated in the aforesaid Jorgensen Patent 2,324,509 and in Fig. 4 of the present disclosure. Its components include a vamp 10, an insole 11, a lining 12, a 25 thermoplastic toe-stiffener 13 and a doubler between the toe-stiffener and the vamp. For the sake of simplicity the drawing represents the vamp and the doubler as merged in one ply instead of representing them individually.

30 In the usual course of making a shoe of this type the toe-lasting operation is performed by one machine after the sides have been lasted by another machine. Furthermore, the toe-lasting machine disclosed in the aforesaid Jorgensen 35 patent includes means for applying lasting cement to those surfaces of the insole and the vamp that are to be pressed one against the other by the lasting wipers. Those surfaces should be nearly if not quite dry when the lasting 40 cement is applied to them, because any considerable moisture on them would impair the adhesive effect of the cement.

The shoe-treating apparatus herein described includes a casing 15 that provides a treatment 45 chamber 16 of two-shoe capacity into which the foreparts of shoes may be inserted through individual openings as represented in Fig. 2. Atmospheric pressure is maintained in this chamber except as it may be exceeded in negligible degree when escape of air and steam is obstructed by shoes undergoing treatment. The walls of the chamber 16 are thick and composed largely of heat-insulating material 19, but the top and bottom are lined, respectively, with confronting 50 metallic heat-radiating members 17 and 18 in

which electrical heat-generators 20 are embedded. The members 17 and 18 are spaced one from the other far enough to clear the toes of shoes inserted between them.

Steam conducted to the member 17 by a tube 21 flows through a crooked conduit 22 in which it is superheated and from which it is eventually emitted into the chamber 16 in many small jets through ports 23 arranged to direct the jets toward the heat-radiating member 18. The member 17 is capable of superheating the steam to a temperature of at least 260° F.

Air above atmospheric pressure is conducted to the member 18 by a tube 25 and thence through a crooked conduit 26 in which it is superheated and from which it is eventually emitted into the chamber 16 from small ports 27 arranged to direct jets toward the heat-radiating member 17. The member 18 is capable of superheating the air in the conduit 26 to a temperature of at least 356° F.

The steam-ports 23 are arranged in two groups, one for each of two shoes standing side by side and projecting into the treatment chamber as represented in Fig. 2. The ports of each group are so situated as to flow steam downwardly on the outer surface of the vamp 10 (Fig. 4), and they are so numerous that a toe-stiffener 13 may be conditioned for lasting in about $\frac{1}{3}$ minute. Meanwhile, jets of hot air emitted by the ports 27 impinge against the bottom of the insole 11 and the margin of lining 12. As hot air flows under the margins of all the layers of upper materials, it has enough velocity to blow away all steam that would otherwise enter the space bounded by those margins, the member 18 and the insole. The heat is supplied to the toe-stiffener partly by convection, partly by conduction, and partly by radiation from the members 17 and 18, the conduction being accelerated by the moisture content of the steam.

Each treatment station is provided with a bar 28 for supporting the heel end of a shoe, with a sill 29 on which the ball portion of the shoe may stand, and with an arch 30 divided into individually adjustable segments adapted to be flexed by the forepart of the shoe and to conform thereto, the arch being composed of some resilient material such as felt, and its effect being to restrict the influx of cool air to the chamber 16 and the efflux of hot air therefrom.

Fig. 1 includes conventional representations of an air-pump 31, a low-pressure boiler 32, and other elements combined therewith for supplying steam to the tube 21 in regulatable quantities, and hot air in regulatable quantities to the tube 25. The boiler 32 is a closed, pressure-sustaining vessel containing an electric heating unit 33 of the immersion type. The boiler will be supplied but not filled with water 34 to be boiled, but a space will be provided for steam above the water.

Air will be supplied by the pump 31 and forced above atmospheric pressure through a tube 35 and thereby conducted to one of a series of fittings all in potential communication with one another and including four needle-valves 36, 37, 38, and 39. These valves and other fittings are assembled and connected in a metallic casing 40 in which an electric heat-generator 41 is embedded. Molten lead 42 or some alloy, poured into the casing 40 after the fittings are assembled therein, fills the casing and conducts heat therefrom to the fittings. All the fittings through

which air and steam are conducted may therefore be maintained at a high temperature by the element 41.

In practice, the valves 36, 37, and 39 will be left open when it is desired to treat shoes as hereinbefore specified, and the valve 38 will remain closed except when it is desired to modify the treatment as hereinafter explained. Continuing on the basis of leaving the valve 38 closed, some of the air pumped through tube 35 will flow through valve 37, tube 25 and superheater 18 to be emitted with considerable velocity by the ports 27 (Fig. 4). At the same time some of it will flow through valve 36, tube 43 and boiling water 34. A mixture of air and steam will flow from the boiler 32, through tube 44, valve 39, tube 21, superheater 17 and emission ports 23. Although some air is mixed with steam in the boiler, it is so thoroughly saturated with moisture while bubbling through the boiling water that it has little, if any, diluting effect upon the steam.

If the character of the work or the conditions of treatment suggest that a small quantity of steam would be beneficial if mixed with the air flowing through the tube 25, it can be supplied through the valve 38.

Having described my invention, what I claim as new and desire to secure by Letters Patent of the United States is:

1. That improvement in methods of treating a partially fabricated shoe having a thermoplastic toe-stiffener, which consists in flowing steam on the outer surface of the vamp until the toe-stiffener covered thereby is rendered limp, and simultaneously flowing hot air on the bottom of the insole in sufficient volume and with sufficient velocity to prevent the steam from wetting the insole.

2. That improvement in methods of treating a partially fabricated shoe having a thermoplastic toe-stiffener, which consists in directing a plurality of jets of steam against the outer surface of the portion of the vamp that masks the toe-stiffener, and simultaneously directing a plurality of jets of hot air against the bottom of the forepart of the insole.

3. That improvement in methods of treating a partially fabricated shoe having a thermoplastic toe-stiffener, which consists in emitting pressure steam downwardly against the outer surface of the portion of a vamp that masks the toe-stiffener, and simultaneously emitting hot air above atmospheric pressure upwardly against the bottom of the forepart of the insole in sufficient volume and with sufficient velocity to blow the steam away from the insole.

4. That improvement in methods of treating a partially fabricated shoe having a thermoplastic toe-stiffener, which consists in heating and wetting the toe-stiffener and the corresponding area of the vamp with steam above the temperature of boiling water, and simultaneously blowing the surplus steam away from the insole with compressed air hotter than the steam and impinging against the bottom of the insole.

5. Shoe-treating apparatus comprising means forming a treatment chamber having an opening to receive the forepart of a shoe, two confronting heat-radiators in said chamber each having a heat-generator and a conduit, means for supplying steam to one of said conduits, and means for supplying air above atmospheric pressure to the other one of said conduits, said conduits having outlets arranged to emit jets of steam and air respectively against opposite sur-

faces of a forepart interposed between said radiators.

6. Shoe-treating apparatus comprising means forming a treatment chamber having an opening to receive the forepart of a shoe, a conduit having an outlet for emitting a jet of air in said chamber, means for supporting a shoe in a position to locate the bottom of its forepart across the jet so emitted, means for supplying air above atmospheric pressure to said conduit, a steam-conduit having an outlet for emitting a jet of steam against the outside of the vamp of a shoe so positioned, and means for supplying steam to said steam-conduit.

7. Shoe-treating apparatus comprising means forming a treatment chamber and including a wall having an opening to receive the forepart only of a partially fabricated shoe, means for emitting one or more jets of steam against the outside of the vamp of a forepart in said chamber.

ber, and means for emitting one or more jets of hot dry air against the outside of the forepart of the insole in sufficient volume and with enough velocity to prevent the steam from wetting the insole.

8. Shoe-treating apparatus comprising means forming a treatment chamber and including a wall having an opening to receive the forepart only of a partially fabricated shoe, said means also including two heat-radiating members confronting each other and spaced to receive the work between them, means for heating said members, means thermally related to one of said members for emitting jets of steam toward the other, and means thermally related to said other for emitting jets of hot dry air toward said one.

MIETH MAESER.
